Continuation of application Serial No. 344,772,
March 6, 1929. This application April 14, 1933,
Serial No. 666,162

4 Claims. (Cl. 250—27.5)

This application is a continuation of my co-pending application Serial No. 344,772, filed March 6, 1929, now Patent 1,944,190, issued Jan. 23, 1934, and the invention herein described is 5 disclosed in Fig. 7 of this copending application.

My invention relates to electron discharge tubes having a control electrode and particularly to electron discharge tubes designed for generating large amounts of power or for generating very 10 high frequency currents.

It has hitherto been proposed to make the control electrode a cylindrical body with longitudinally extending grooves therein, and to place the filaments forming the cathode structure of the 15 tube at the bottom of the grooves. I have found, however, that when the grid is positive this large mass of material substantially enclosing the filament absorbs a large part of the electrons emitted from the filament, and hence cuts down the plate 20 current to the anode. I have further found that the enclosing grid structure of this type of tube narrows the beam of electrons directed towards the anode with the result that they are concentrated on a small portion of the area of the anode 25 and cause overheating and puncture of the tube at these particular areas. Furthermore, in order to have an appreciable value of amplification, the filaments must be located very close to the bottom of these grooves with the result that any sagging of the filament is likely to cause the filament to touch the surrounding grid structure and 30 short circuit thereto.

I avoid these disadvantages of the prior art construction just referred to by having a built up 35 central grid structure with radial projections therefrom having enlarged ends and by locating the filaments so that they are adjacent only to these enlarged ends and not to the remaining sections of the grid structure.

40 Other features and advantages of my invention will appear from the following description taken in conjunction with the accompanying drawing in which:

Figure 1 is a view in longitudinal section of a 45 power tube constructed in accordance with my invention; and,

Fig. 2 is a view in lateral section taken on the line II—II of Fig. 1 with the details of the upper 50 end portion of the tube left out for the sake of clearness.

Referring to the drawing the apparatus comprises a vacuum tight container formed by an outer metal tube 10 which acts as the anode and which is closed at the upper end by a metal piece 55 integral with the tube. The lower end of the tube

is closed by means of a glass member 12 which is sealed to it by means of a metallic reentrant portion 13 sealed to a reentrant portion of the glass member 12 at the seal 14.

The metallic reentrant portion 13 forms the 5 structural part of the grid of the power tube and is in the form of a metal tube 15 closed at the upper end by means of a metal piece integral with it. A pipe 16 is positioned within and spaced from the tube 15. By means of this structure the 10 grid may be cooled by forcing water or some other cooling fluid into the reentrant portion 13 between the tube 15 and the pipe 16 and out through the pipe 16.

Surrounding the pipe 15 is a tube 18 to which 15 a plurality of U-shaped members 19 of sheet material are welded or otherwise suitably attached. These members are assembled in contact with each other to form ribs projecting laterally from the tube 18. Each rib supports a rod 20 welded 20 or otherwise suitably attached thereto in such position that it is parallel and adjacent to a filament 21, whereby a very effective grid control is obtained. The control effect is exerted by the rods 20 while the ribs formed by members 19 conduct the heat away from the rods.

The upper ends of the filament 21 are supported and electrically connected by means of rods 22 secured to a metal ring 23. The supporting structure for the ring 23 comprises a rod 24 30 of insulating material such as quartz that is clamped in a split supporting member 25 which is welded or otherwise attached in any suitable manner to the upper end of the reentrant portion 13. The ring 23 is attached to the upper end 35 of the rod 24 by means of another split supporting member 26 which is attached to the ring 23 and clamped to the rod 24.

The lower ends of the filaments 21 are attached 40 to rods 27, supported by means of rings 28 which are bolted to terminal rods seated in the reentrant portions 29 of the glass member 12. Several filaments are supported by each of these rings 28.

It will thus be noted that I have provided an 45 electron discharge device with an exterior anode and a central control electrode or grid structure and a cathode structure comprising a plurality of filaments intermediate the central electrode structure and the exterior anode. The filament 50 structure is placed adjacent to the outer enlarged ends of the control electrode and hence the grid structure will not absorb a large mass of electrons when the grid is positive, as would be the case if the filaments were located well within 55

the U-shaped members 19. The enlarged ends 20 of the radial projecting portion of the grid will thus control the anode current without producing a detrimental robbing effect thereon. The 5 electrons passing from the filament 21 to the anode 10 will have a large area upon which to strike the anode 10 and will not be restricted to a small area, as they would be if they were located in the bottom of the trough formed by 10 the U-shaped members 19.

Various modifications may be made in my invention without departing from the spirit and scope thereof, and I desire, therefore, that only such limitations shall be placed thereon as are 15 shown by the prior art and set forth in the appended claims.

I claim as my invention:

1. An electron discharge device comprising a vacuum tight container, an anode constituting 20 a portion of the outer wall thereof, a control electrode within said container and having projections extending towards said anode and a cathode structure intermediate said control electrode and said anode, and closer to the latter 25 than are the ends of said projections.
2. An electron discharge device comprising a vacuum tight container, an anode constituting a portion of the outer wall thereof, a control electrode structure within said container, means for 30 directing a cooling medium to a portion of said

control electrode structure, radial projecting portions of said control electrode structure extending toward said anode, and a cathode structure intermediate said control electrode structure and said anode, and spaced closer to the outer ends 5 of said radial projecting portions than to the remainder of said control electrode structure.

3. An electron discharge device comprising a vacuum tight container, an anode constituting a portion of the outer wall thereof, a control electrode structure within the central portion of said container, radial projecting portions of said control electrode structure extending toward said anode, the outer ends of said portions being greatly enlarged over the intermediate section of 15 said radial projecting portions and a cathode structure intermediate said control electrode structure and said anode, and spaced closer to the outer ends of said radial projecting portions than to the remainder of the control electrode 20 structure.

4. An electron discharge device comprising a control electrode having radial projecting portions, a cathode structure comprising filaments and an anode surrounding said control electrode 25 and said cathode structure said filaments being closer to the anode than the ends of said radial projecting portions.

ILLIA E. MOUROMTSEFF. 30
